UNITED STATES PATENT OFFICE.

ERNST KOERTING, OF PEGLI, ITALY, ASSIGNOR TO SCHUTTE & KOERTING COMPANY, OF PHILADELPHIA, PENNSYLVANIA, A CORPORATION OF PENNSYLVANIA.

STEAM-CONDENSER.

No. 926,198.

Specification of Letters Patent.

Patented June 29, 1909.

Application filed July 30, 1908. Serial No. 446,103.

To all whom it may concern:

Be it known that I, ERNST KOERTING, a subject of the Emperor of Germany, and a resident of Pegli, Italy, have invented certain new and useful Improvements in Steam-Condensers, of which the following is a full, true, and concise specification.

This invention is an improvement in steam or vapor condensers and relates to condensers employing a water shower in a vacuum chamber, the object of the invention being to accomplish a rapid and thorough condensation or absorption of all the steam or vapor and a simultaneous effective removal 15 of the permanent gases therein.

The drawings forming a part hereof indicate the principle of operation of my invention, but are not intended to indicate details of mechanical design, which latter may 20 be varied according to the option of the builder.

Figure 1 represents in central vertical section, parts being shown in elevation, a simple form of apparatus embodying my invention; 25 and Fig. 2 is a similar view of a developed and preferred form.

Referring to Fig. 1, the condensing chamber is formed by a main casing 1 provided with water distributing means at its upper 30 end and with a water receiver at its base which is connected with the suction-pipe 2 of a pump P of any suitable construction, by means of which the condensing water and water of condensation may be discharged 35 and exhausted from the casing. The interior of the condensing chamber is divided into two compartments by means of an upright partition wall 3, which is preferably a cylindrical casing, located concentrically 40 within the main casing and open at its bottom so that the two compartments thus formed are both in communication with each other and with the water receiver in the base. The steam to be condensed is introduced 45 into one of the compartments, preferably the outer compartment, from an annular steam channel 4 which girdles the main casing and communicates with the interior thereof through a series of openings or inlets 5, said steam inlets being located at the upper part of the compartment just beneath the entrance of the water thereto. The

water distributing means for the outer compartment consists of an annular chamber 6 united to or formed as a part of the main 55 casing in any convenient manner, and which is provided with a number of fine perforations in its bottom wall through which water is showered into the condensing chamber. The central casing 3 opens upwardly through 60 the annular shower-head 6 into an auxiliary casing 7 which is also supplied with a suitable shower-head 8 by which water may be likewise showered through the inner compartment. The water connections of the 65 two shower-heads are supplied with cocks 9 by which the water may be shut off from one or both as desired. The auxiliary casing 7 provides an annular space near the entrance 70 of water to the inner compartment into 75 which gases may rise and collect, and an exhaust passage or pipe 10 is connected with such gas collecting space whereby the gases therein are forcibly removed from the condensing chamber. 75

As shown in Fig. 1 the gas exhaust passage leads directly to the suction pipe 2. In operation, the pump maintains a partial vacuum within the casing and the steam and gases admitted from the steam inlet pass first 80 downwardly in the direction of the shower, by which the greater part of the moisture is condensed and carried off through the water discharge, while any remainder of uncondensed steam as well as the permanent gases 85 in the chamber, pass beneath the lower edge of the partition wall 3 and move upwardly in the inner compartment against and through the shower of water therein, to the 90 region of the gas exhaust outlet and the 95 gases then remaining are drawn off and discharged through such outlet to the suction of the pump. In rising through the inner compartment the gases encounter water of increasing coolness and leave the apparatus after having been in contact just beneath 100 the shower-head, with the freshest and coldest water. Such gases as may become imprisoned in the water that collects in the water receiver are given opportunity to rise to the surface and travel upwardly through the inner compartment by the provision of a gas-trap in the discharge passage. Such trap is provided by an inverted pocket 11

covering the water outlet and extending somewhat below the same, as shown.

Referring now to Fig. 2, the construction of condensing chamber, showering means and water discharging means may be the same as shown in Fig. 1 and above described, but in this form of the invention the means for exhausting the gases from the condensing chamber consist of two or more steam 5 aspirators connected to the gas-collecting space of the condensing chamber in tandem relation so that the second aspirator will assist the action of the first, and the third 10 the second, and so on. The drawing illustrates two aspirators of familiar construction, thus connected, and acting to remove the gases and augment the vacuum produced by the pump. The one indicated by 15 12 has its suction pipe connected with the gas-collecting chamber of the inner compartment and exhausts into a separate condensing receptacle 13 which is supplied with cold water from a pipe 14, the overflow being drawn off through a waste-pipe 15 by the 20 pump P. The second aspirator, designated 25 16, has its suction connected to the condensing receptacle 13 so that the vacuum in the latter is thereby increased and the effect of the first aspirator correspondingly 30 magnified. A second condensing receptacle can be provided for the second aspirator, similarly connected, and so on, according to the number employed.

Having described my invention, what I 35 claim and desire to secure by United States Letters Patent is:

1. In a condenser a chamber divided into compartments in communication with each other at the bottom, a steam inlet to the 40 upper part of one of said compartments and a gas exhaust passage leading from the other compartment, and means for passing water through each compartment of the said chamber.

45 2. A condenser comprising a chamber containing a partition wall dividing the same into inner and outer compartments which communicate at their bottom, and means for showering water through and discharging it from said chamber, in combination with a steam inlet into one of said compartments and a gas exhaust passage leading from the other.

50 3. A condenser comprising a casing supplied with showering means at its upper part and a steam or vapor inlet, an inner casing centrally disposed with respect to said showering means and opening upwardly through the same, a second showering means for said inner casing and means for withdrawing gases from said inner casing.

55 4. A condenser comprising a casing supplied with a steam or vapor inlet and showering means at its upper part, an inner casing centrally disposed with respect to said

showering means, and provided with a second showering means in combination with an exhaust passage leading from the upper part of said inner casing, and means for withdrawing the gases therethrough.

5. In a condenser the combination with the condensing chamber, water distributing means therefor and a pump for exhausting water from said chamber, of a partition wall dividing said chamber into compartments 75 which communicate at their bottom, a steam or vapor inlet to one of said compartments and a gas exhaust passage for the other compartment having a connection with the suction pipe of the aforesaid pump.

6. In a condenser the combination with the condensing chamber having water distributing means and a pump for exhausting the water, of an aspirating apparatus acting to exhaust gas from said chamber and including a discharge receptacle, a waste water pipe connecting said receptacle with the suction of the pump and means for removing the gases from said receptacle under reduced pressure.

7. In a condenser the combination with the condensing chamber, means for passing water through the same, of a steam aspirator acting to exhaust gas from said chamber, a condensing discharge receptacle for said aspirator having a gas collecting space and means for withdrawing the gases therefrom.

8. In a condenser the combination with the condensing chamber and water distributing means therein, of a steam aspirator acting to exhaust gas from said chamber and having a condensing discharge receptacle, a pump for discharging the waste water from said receptacle and means for removing the uncondensed gas from said receptacle under 105 reduced pressure.

9. In a condenser the combination with the condensing vacuum chamber and means for passing water therethrough and provided with a gas collecting and conducting space, of two or more steam jet aspirators connected with said space in tandem relation to each other and having a condensing receptacle interposed between the exhaust of one and the suction of the other, and means for 110 withdrawing the water from said receptacle.

10. In a condenser, a condensing chamber provided with a gas collecting and conducting space and water distributing means and a water exhaust pump in combination with two or more steam-jet aspirators connected to said space in tandem relation to each other and having a condensing receptacle interposed between the exhaust of one and the suction of the other, and a waste water pipe 115 for said receptacle connected to the suction of the said water pump.

11. In a condenser a condensing chamber, water distributing means therefor, and a partition wall dividing said chamber into 130

compartments provided respectively with a steam or vapor inlet and a gas exhaust passage, in combination with a steam aspirator connected to said exhaust passage and having a condensing discharge receptacle and a rarefying means for said discharge receptacle.

In testimony whereof, I have signed my

name to the specification in the presence of two subscribing witnesses.

ERNST KOERTING.
